Des. 203,424
Patented Jan. 4, 1966

203,424

MANNED SPACE STATION VEHICLE

Lawrence Bernard Rellis, San Diego, Calif.
(734 NW. 80th St., Miami, Fla. 33150)

Filed Apr. 21, 1964, Ser. No. 79,630

Term of patent 14 years

(Cl. D71—1)

Fig. 4

Fig. 5

FIG. 1 is a perspective view of the manned space station vehicle in orbital flight position showing my new design.

FIG. 2 is a bottom plan view thereof, the top is shown in the perspective view FIG. 1;

FIG. 3 is a front elevation view in the landing position;

FIG. 4 is a side elevational view thereof, the opposite side being a mirror image; and

FIG. 5 is a rear elevational view in the landing position.

I claim:

The ornamental design for a manned space station vehicle, as shown and described.
